Walter K. Wolf

BY

W. K. Wolf, ATTORNEY

UNITED STATES PATENT OFFICE.

WALTER K. WOLF, OF BROWNSTOWN, PENNSYLVANIA.

LOSS-PREVENTING DEVICE.

942,695.

Specification of Letters Patent. Patented Dec. 7, 1903.

Application filed March 1, 1903. Serial No. 480,622.

To all whom it may concern:

Be it known that I, WALTER K. WOLF, a citizen of the United States, residing at Brownstown, in the county of Lancaster and

5 State of Pennsylvania, have invented a certain new and useful Improvement in Loss-Preventing Devices, of which the following is a specification.

My invention relates to a new and useful 10 improvement in hat pins, and has for its object to provide an exceedingly simple, and effective device of this character, whereby a hat pin may be provided with a safety holding device in the form of an ornament.

15 A further object of my invention is to provide a device of the character described in which a safety holding device is provided for the pointed end of the pin which may be readily placed thereon or removed 20 therefrom.

With these ends in view, this invention 25 consists in the details of construction and combination of elements hereinafter set forth and then specifically designated by the claim.

In order that those skilled in the art to which this invention appertains may understand how to make and use the same, I will 30 describe its construction in detail, referring by letter to the accompanying drawing forming a part of this specification, in which—

Figure 1 is a side elevation of a hat pin made in accordance with my improvement. 35 Fig. 2, an end view thereof with the clutch member removed. Fig. 3, a sectional view at the line $x-x$ of Fig. 1 looking in the direction of the arrows. Fig. 4, a longitudinal sectional view thereof. Fig. 5, a back view of the clutch or grip showing the spring attached thereto, and Fig. 6, a similar 40 view, the spring being detached.

In carrying out my invention as here embodied, A represents the hat pin having a 45 head B and a pointed end C. On the pointed end of the pin is placed the safety holding device D, which is formed to represent some flower or other suitable ornament, said safety device consisting of the stem E provided with the conical opening F, which acts 50 as a guide for the pin A, said conical opening terminating in the hole G, which is directly in alignment with the hole H formed

in the clutch or grip I, which is provided with the lugs or shafts J, which are journaled in the lower leaf K of the safety device. 55

In one side of the clutch I is formed the notch L, through which extends the coils of the spring M, which is coiled about one 60 of the shafts J, one end of said spring adapted to rest against the clutch, the other end against the lower leaf K, so that said clutch is normally pressed inward or toward the stem E of the safety device. The upper 65 end of the clutch I is curved outward, as indicated by N, so that when the upper leaf O of the safety device, which is pivoted to the stem E, by the pin P is pressed downward, it will cause the upper end of the 70 clutch I to move outward until it has taken a vertical position, at which time the pin A may be withdrawn from the safety device.

In practice the hat pin is placed in the 75 hat and the safety device is placed on the end of the pin, and by pushing it along said pin, said pin will first enter the conical opening F, then the hole G and finally the hole H in the clutch I, and as soon as the safety device is let go of, the spring M will cause the 80 clutch I to move out of a vertical line, thus causing the clutch or grip I to take hold of the pin at two points, which will prevent the safety device from being removed, until the upper leaf O is pressed downward, at 85 which time, because of the curved upper end N of the clutch or grip will cause said clutch to move to the vertical line, allowing the hat pin to be withdrawn.

One of the important features of my invention is that the safety device may be placed on the pin a sufficient distance for the clutch to take hold of said pin, but at said distance the point of the pin will not protrude from said safety device, thus preventing the pin from coming in contact with a person, which would possibly injure said person. 90 95

Another feature is, that various designs of safety devices may be used with a single 100 pin, so that the user may use the device with different ornaments, thus varying the appearance from time to time as may be desired.

Of course I do not wish to be limited to 105 the exact details of construction here shown,

as these may be varied within the scope of the appended claim without departing from the spirit of my invention.

Having thus fully described my invention, what I claim as new and useful, is—

As an article of manufacture, a safety device consisting of a stem having a conical opening terminating in a hole formed therein, a lower leaf secured to said stem, an upper leaf pivoted to said stem, a clutch member provided with shafts and having a hole and a notch formed therein, said clutch member adapted to be journaled in the lower

leaf by means of the shafts, and a spring coiled about one of said shafts, one end of which rests against the clutch member, the opposite end against the lower leaf, substantially, as shown and described.

In testimony whereof, I have hereunto affixed my signature in the presence of two subscribing witnesses.

WALTER K. WOLF.
